DISPLAY CARD FOR TRANSPORTATION
ADVERTISING

Meyer Gold, Minneapolis, Minn.

Application April 11, 1941, Serial No. 388,067

2 Claims. (Cl. 40—12)

This invention relates to advertising placards and particularly to display cards used in buses, streetcars, railroad cars and other vehicles where advertising space is available at the upper and concavely curved or arched portions of the interior walls. Such space has been widely used for advertising purposes because of the effective visibility of concavely flexed display cards mounted therein to passengers sitting or standing in the car.

It is an object of my present invention to provide an advertising placard for use in public transportation vehicles which has embodied therein a "stand-out" section disposed substantially in a plane when the card is mounted to conform to the concave shape of the backing surface or wall and thereby contrasting prominently with the flexed card or sheet to effectively attract attention.

It is a further object to provide a very simple, inexpensive and effective advertising placard of the class described which has a display section standing out or protruding from the concave surface of the placard proper when it is flexed, but, nevertheless, lying substantially flush with the card proper when the latter is disposed flatwise for shipping or handling.

A more specific object is to provide an advertising placard of the class described having a display section attached at its upper and lower edges to a somewhat flexible card of larger size and being of substantially equal length to the portion of said card between said attached edges, but having one or more folds to cause such section to be protruded in a plane forwardly of said card when the latter is flexed to a concave position.

These and other objects and advantages of the invention will be more apparent from the following description made in connection with the accompanying drawing, wherein like reference characters refer to the same parts throughout the views, and in which:

Fig. 1 is a front elevation showing an embodiment of my invention applied to an upper arched or concave portion of a wall for advertising purposes;

Fig. 2 is a cross section taken on the line 2—2 of Fig. 1;

Fig. 3 is a sectional, perspective view showing one of my placards of the form disclosed in Figs. 1 and 2, compactly disposed in flatwise position;

Fig. 4 is a front elevation of a somewhat different form of the invention;

Fig. 5 is a cross section taken on the line 5—5 of Fig. 4, and

Fig. 6 is a sectional perspective view of the placard shown in Figs. 4 and 5.

Referring now to the form of the invention shown in Figs. 1 to 3, inclusive, an advertising card body 7 of rectangular shape constructed from moderately flexible sheet material such as cardbord or the like is shown, having printed or otherwise reproduced on the outer face thereof advertising or display matter.

Covering a portion of the card or flexible body 7 is a display section 8 which may be constructed in a very wide range of shapes, having its upper and lower edges secured to the outer face of said card, preferably along straight lines extending parallel with the corresponding card edges. The length or height of said display section 8 between said attached portions is equal to the portion of said card covered by said section so that when card 7 is disposed flatwise section 8 will lie substantially flush therewith. The attachment of section 8, as shown in Figs. 1 to 3, is preferably made by inturning the lower edge of said section to form a narrow, upstanding attachment flange 8a which is connected by any suitable attachment means such as adhesive or fasteners to said card. Section 8 is folded, creased, or scored a short distance below its upper attached edge along a line x disposed parallel to the upper edge of card 7 to form an outwardly disposed folded corner when card 7 is flexed concavely. The upper extremity of section 8, as shown, is folded along a second line parallel to the upper edge of the card to form an upstanding attachment edge 8b which is secured by suitable means such as adhesive or fasteners to the upper portion of card 7. It will be apparent that the attachment flange 8b as well as the narrow transverse portion numbered 8c connecting the display section proper with the attachment flange can be constructed from a separate piece or strip of material and secured to the back of the display section proper.

In the particular embodiment shown in Figs. 1 to 3, my placard is designed for advertising men's shirts and the "stand-out" display section 8 is formed in the shape of a shirt folded as it is sold or comes from the laundry. Here the upper collar portion c of the shirt is cut out from the stock of the connecting portion 8c to form a continuation in the same plane of the body of section 8 when the section is protruded by concavely flexing the card 7.

My advertising placards are cooperatively as-

sociated with the arched or concave display panels, as shown, by attachment of the upper and lower edges of the card 7 to retaining strips 9 or other means usually provided in the advertising spaces of public transportation vehicles. In conventional car advertising the strips 9, as shown in the drawing, have panels which are adapted to over-lie the horizontal edges of the placard supported, and said strips are spaced at such distance apart that the placard or card 7 when attached and flexed, will conform to the concave shape of the panel.

As shown in Fig. 3, when my card 7 is disposed flat-wise, the "stand-out" display section 8 lies flush against the card and a number of the devices may be stacked for shipping or handling in a compact body.

When the card 7 of my device is attached to an arched or concave advertising panel, the section 8 is automatically protruded as the card is flexed, folding on the transverse line x and disposing the display body of section 8 in a plane inclined somewhat to the vertical and protruding considerably from the concave card. The positioning of display section 8 is very effective for visibility, being disposed in a plane outwardly of the card proper and therefore attracts attention to the entire display and the advertising material appearing on the card proper as well as the protruded display section.

In Figs. 4 to 6 I have shown a somewhat simplified form of my invention wherein the "stand-out" display section 18 is formed integrally with the flexible body or card 7. Here a die or other means for cutting the side edges of display section 18 is utilized economically, and at the same time a scoring die may be used to make provision for the fold x spaced downwardly a short distance from the upper attached end of section 18. This display section 18, including the connecting transverse portion 18c, is disposed in the plane of the card 7 when said card is laid flat-wise, and

a number of said cards may be thus stacked or packaged for handling a shipment in less space than the form of my invention illustrated in Figs. 1 to 3.

5 From the foregoing description it will be seen that I have provided a very simple, inexpensive but highly effective advertising placard for use in public transportation vehicles or other display locations where arched or concave advertising

10 panels are provided.

It will, of course, be understood that various changes may be made in the form, details, proportions and arrangement of the several parts without departing from the scope of my invention.

15 What is claimed is:

1. An advertising display comprising, in combination with a pair of spaced devices that are opposed to retain two opposite edges of a panel or the like, a somewhat flexible placard of such dimension that it must be in concavity when two of its opposed edges are engaged by said spaced devices, a substantially flat display sheet hinged at one edge directly to said placard along a line substantially parallel and adjacent to one of the retained edges of the placard, and a stiff but bendable strip of material connecting the opposite edge of said sheet to the placard, said strip having a fold line substantially parallel to said hinged edge and being of such width as to urge the sheet automatically away from the placard when the latter is retained in concavity by said devices while permitting the sheet and placard to assume a substantially flush relationship when the latter is released.

2. In the combination defined in claim 1, said display sheet comprising an element separate from said placard and attached thereto solely by said hinged edge and said bendable strip, the latter being an integral part of said sheet.

MEYER GOLD.
